FREDERICK MACDONALD FAIRGRIEVE AND ARCHIBALD FAIRGRIEVE, OF TORONTO,
ONTARIO, CANADA.

TUB FOR WASHING MACHINES.

Application filed January 24, 1924. Serial No. 688,277.

The principal objects of the invention are to provide a tub which will eliminate splashing and the slopping of water about when wringing or removing the clothes therefrom, 5 and to devise a tub of sheet metal construction which will be easily kept clean, is of extremely light weight and very strong and durable.

The principal features of the invention 10 consist in forming a concaved or dished top to direct the wash water from splashing against the cover in the washing operation and to lead the water into the tub when removing the clothes or wringing, and further 15 in flanging the edges of the ends inwardly in a curved flange and connecting same to the body in a double or lock seam.

A still further feature consists in arranging 20 an axial support in the form of dished discs secured to the radially ribbed ends and provided with keystone shaped slots opening from the underside to receive tapered trunnions.

In the drawings Figure 1 is a perspective 25 view of our improved tub.

Figure 2 is an enlarged side elevational and half vertical sectional view.

Figure 3 is an enlarged end elevational and half vertical section.

30 Figure 4 is an enlarged perspective detail of one of the end supports.

The body 1 of the tub is substantially cylindrical having an opening 2 in the top 35 extending from end to end. Within the opening 2 is arranged a top sheet 3 which is secured to the body 1 with a double or lock seam 4 which gives great rigidity to the structure. The top is formed with a central circular opening 5 into which a suitable 40 cover is inserted.

The dished shape of the top drains any water falling on the top into the tub and thus prevents the slopping of water outside the tub when the clothes are being removed.

45 A flange 6 is secured on the inner side of the top around the opening 5.

An opening 7 is formed in the bottom of the body 1 and extends from end to end and secured to the longitudinal edges of this 50 opening by a lock seam 8 is a ridge piece 9 which is of an inverted V shape formed with a rounded top 10 and filleted bottom portions 11 merging into the curve of the bottom of the body. The member 9 is 55 drawn from sheet metal and the ends 12

slope downwardly and outwardly to the line of the cylindrical body and form a continuation of the end edges thereof.

The ends 13 of the body are of substantially circular form and are pressed with 60 the rounded flanged edges 14 which are joined to the end edges of the body and bottom ridge piece 9 in a lock seam 15. By thus shaping the ends with the rounded flanges the interior of the tub is completed 65 without any sharp corners where dirt may lodge. Consequently the tub may be kept quite clean.

The ends 13 are strengthened by stamping 70 therein a plurality of radial ribs 16 which add stiffness and rigidity to the whole structure.

Secured to the outer sides of the ends and centrally thereof are the dished discs 17 of 75 heavy sheet metal. These discs are formed with flattened faces 18 and slots 19 are cut through the sloping portion and flattened ends opening from the bottom and having upwardly converging side edges 20 forming 80 keystone shaped slots.

Into the slots 19 are fitted cast metal 85 blocks 21 of keystone shape having the converging sides 22 shaped with a bevel thus forming a dove-tail structure which when inserted into the slots 19 of the discs 17 draws tightly into place, the inner faces of 90 the blocks seating against the ends 13 of the tub.

The blocks 21 are provided with gudgeon 95 pins 23 which form the trunnions upon which the tub is pivotally supported in suitable bearings. The gudgeons are of course held in suitable bearings in a supporting frame, which is not shown and by reason of the taper structure of the blocks 100 and the slots 19 of the end plates the tub may be easily removed and may be as easily replaced and when in engagement the tub is very securely supported.

In use the tub is oscillated by suitable 105 means and the water and clothes are washed back and forth. The water washes up the rounded body 1 and striking the inturned dished top 3 is directed downwardly and away from the cover and with the addition of the flange 6 the water is prevented from splashing out through the contact of the cover joint, even though said joint may not be tight.

In the return swing of the tub the water 110

and clothes strike the bridge piece 9 and a rubbing and cleansing action occurs, the water being forced through the fabrics. The rounded top of this bridge piece with the filleted corners presents smooth rounded surfaces to the clothes in action so that they will not be torn or injured.

A tub constructed of sheet metal as described is extremely light and is therefore operated with the minimum effort, the dishing and ribbing of the ends and the securing of the ends by double seams renders the structure extremely rigid and strong and a very serviceable and also good appearing article is produced.

What we claim as our invention is:—

1. A tub for a washing machine having a rectangular opening in the top extending from end to end, a top piece secured to the edges of said opening by a ribbed seam and

having a central cover opening and being dished inwardly to said cover opening, a cover closing said opening and formed with a downwardly extending flange adapted to engage the edge of said opening, and a flange spaced back from the edge of said opening and extending downwardly from said top piece to form a baffle spaced from said cover flange.

2. In a tub for a washing machine having rigid ends, dished sheet metal plates secured to said ends and formed with tapered slots opening downward, supporting blocks having tapered edges to enter said slots to support the tub and channels formed in said tapered edges to receive the edge portion of said tapered slots to lock the tub against axial movement.
